[57] CLAIM

The ornamental design for a puzzle booklet, as shown and described.

DESCRIPTION

FIG. 1 is a perspective view of a puzzle booklet showing my new design open to the first page;

FIG. 2 is a perspective view thereof with the sealed flap partially pulled away from the page;

FIG. 3 is a perspective view thereof with the flap fully open to reveal the solution to the puzzle;

FIG. 4 is a perspective view showing the rear of the page with the flap open and a typical subsequent page of the puzzle booklet;

FIG. 5 is a perspective view of the last page of the booklet with the flap sealed and flaps of preceding pages open; and

FIG. 6 is a perspective view of the puzzle booklet in closed condition.

The rear cover of the puzzle booklet is plain and unornamented.
